STOKER

Samuel A. Townsend, Jr., Webster Groves, Mo.

Application July 25, 1940, Serial No. 347,407

2 Claims. (Cl. 110—47)

This invention relates to automatic stoker devices particularly adapted for domestic use.

Coal feeding stokers of the household or domestic type, for use with bituminous or other relatively fast burning solid fuels, must be constructed to maintain a relatively deep bed of coals in order to insure holding of the fire during substantial periods when the drafts are reduced and less heat is required. Ordinarily, a stoker for this type of service is provided with one or more retort wells and under-feed means therefor, and manual grates are frequently provided at the sides for desirably extending the bed of coals. These devices require frequent attention to the grates and removal of clinkers.

It is an object of the present invention to provide a more fully automatic stoker of the above type which will maintain a relatively deep, uniformly tapered bed of unconsumed coals, without the necessity of providing the usual manually operable grate extensions, and thus eliminate the usual frequent manual shaking of the grate or removal of accumulated clinkers and ashes in the immediate vicinity of the retort, it being the intention that the invention may be used with a relatively spacious ash pit which requires attention only at very infrequent intervals. Accordingly, a stoker utilizing the present invention approaches substantially closer to the ideal of fully automatic operation than has been the case with stokers heretofore applied to similar use.

In the accompanying drawings which illustrate the invention:

Fig. 1 is a diagrammatic representation showing a portion of a hot air furnace and stoker embodying the invention.

Fig. 2 is a top view of the retort and traveling grate portions of the stoker.

Fig. 3 is a vertical transverse center section through the retort and showing various operating mechanisms.

Fig. 4 is a vertical transverse sectional view taken substantially through the center of the retort and traveling grate structures, as indicated by the section line on Fig. 3.

Fig. 5 is a top view showing a modified form of retort and combination traveling grate and ash conveyor structure.

Fig. 6 is a vertical transverse section of the same taken substantially on the line 6—6 of Fig. 5.

The furnace in Fig. 1 is of the hot air type, though any other type may be used, and comprises an outer wall 10 and inner wall 11, which

may be formed in part of suitable refractory materials, these walls forming the usual air heating space 12 which may be connected by means of pipes 13 to suitable heat discharging registers at remote points. The inner portion of the furnace is connected to a flue 14. The stoker, generally indicated at 15, is mounted on the floor of the furnace between a pair of ash pits 16 provided with doors 17 for access to and removal of the accumulated ashes.

The stoker, as more clearly shown in Figs. 2, 3 and 4, includes a central, elongated portion 20 forming a retort well, and laterally inclined aprons 21, these aprons and the upper portions 5 of the walls of retort well 20 being apertured and forming the usual tuyères. A sheet metal pan 22 underlies the retort well and aprons and includes sharply inclined side portions 23. The whole structure is supported on legs, as at 24, resting on the bottom of the furnace.

Suitably journaled adjacent the outer edges of aprons 21 are a pair of shafts 25 rigidly mounting sprockets 26 and similarly journaled at some distance laterally therefrom are additional shafts 27 mounting sprockets 28. Carried on the sprockets 26 and 28 are chain grate structures 29 which extend from immediately beneath the outer edges of aprons 21 to the adjacent inner edges of ash pits 16. It is assumed that some 20 ash material will slip through grate structures 29 onto inclined pans 23 and this material will slide down these pans and may be removed through doors 30. These doors are shown yieldingly closed by means of overbalanced, weighted 25 levers 31 which will automatically open to release the ash when sufficiently accumulated to lift weighted levers 31. The angle of pans 23, of course, determines the force available for operating doors 30.

An air blower is shown at 32 for forcing air 30 through the duct 33 into the air draft space formed between pan portions 22 and 23 and the retort and traveling grate structures. An under-feed ram is shown at 34 extending through a chute 35 from a point immediately below hopper 36 to the opposite end of retort well 20. Ram 34 is operated by means of a guide block 36a connected by a pitman 37 to a crank arm 38 which is operated by motor 39 through a suitable chain drive 40 and gear box 41. A chain 42 connects motor 39 to blower 32.

The traveling grate structures 29 are operated by means of chains 44 which drive inner journaled shafts 25 through small sprockets 45 and, 45 at their lower extremities, are connected by

means of sprockets 46 to an additional gear box 47. This gear box is, in turn, connected by a sprocket 48 and a chain 49 to a sprocket 50 on the blower shaft. Thus, under-feed ram 34, air blower 32 and the traveling grate structures are jointly controlled by a common motor drive so as to provide for the feeding of fuel and air at the desired relative rates. The motion of grate structures 29 is much slower than is the usual case with ordinary ash conveyors or chain grates, this rate of travel being so correlated with the rate at which the coal is fed to the retort well as to maintain a substantial bed of coal which tapers uniformly from the center of the retort well substantially to the outer edges of the traveling grate structure, as indicated at Y in Fig. 4. As air is fed to the entire expanse of these grate structures, unconsumed coals will be fully burned before being deposited into the ash pit.

In case the stoker is shut down, this relatively deep and extensive bed of coals will maintain a fire for a much longer period than would be the case with the use of an ordinary chain grate, as frequently used with large, industrial boilers. This is of particular importance where bituminous coal is used, since such fuel burns substantially faster than other, more expensive fuels, such as anthracite coal. Moreover, the deep extensive bed of coals provides for adequate heat output for domestic service.

In Figs. 5 and 6 there is shown a modified form in which the retort well 50 and tuyère forming aprons 51 are surrounded by a pair of concentric, apertured plate structures 52 and 53 supported on bearings 54, 55, 56 and 57, in turn carried by legs, as at 58, projecting above inclined portions 23 of the air duct bottom plate structure. Circular plates 52 and 53 are suitably apertured for the transmission of draft air through the supported bed of coals.

The concentric plates are driven by means of motor 39 through a suitable gear box 47a, chain 44a, and shaft 25a journaled in bearing supports 56 and 57. Shaft 25a carries pinions 59 engaging racks 60 and 61, respectively, on plates 52 and 53. Scrapers 62 and 63 are supported above adjacent portions of the traveling plates, as shown.

The operation of this form is as follows:

Feed ram 34 and apertured plates 52 and 53 are operated at such correlated rates as to maintain a relatively deep bed of unconsumed coals extending from the retort well a substantial distance over the traveling grate structures, as in the previous form. In this case, coals on each plate will be conducted around to the associated

scraper 62 or 63 and then diverted outwardly, the size and rate of the plates being such that only fully consumed ash material will be deposited into ash pit 16 by outer scraper 63.

In both forms, the usual daily shaking of the grate for the purpose of dropping ashes into the ash pit is avoided, but at the same time, a relatively deep bed of coals is maintained, as is essential where bituminous fuel is used. Another advantage results from the fact that burning coals are carried by the traveling grate structures outwardly from the retort and thus closer to the air space 12 extending around the furnace, than is the case where a retort alone is used.

Various features may be modified as will occur to those skilled in the art and the exclusive use of all such modifications as come within the scope of the appended claims is contemplated.

I claim:

- 20 1. In a stoker for burning relatively fast burning fuel, a retort well having upper portions and outwardly inclined apron structure containing tuyères, under feed means for forcing fuel into said well and across said apron, perforated traveling grate means extending from immediately beneath the outer edges of said apron structure horizontally a substantial distance outwardly therefrom so as to maintain a bed of fuel of substantial depth adjacent said well, means to apply forced draft to said tuyères and said grate structure, driving mechanism for conjointly operating said under feed and draft means and said traveling grate structure, and means for automatically shifting coal from the inner to the outer edges of said grate structure and for removing ashes from the outer edges of the latter.
- 25 2. In a stoker, a retort well, means for forcing fuel into said well, apron structure extending outwardly and downwardly from the upper portion of said well, horizontal traveling grate means extending from said apron structure a substantial distance outwardly whereby coals traveling by gravity down said apron structure will be caused to accumulate in a bed of substantial depth adjacent said well, tuyère forming perforations in the upper portion of said well, in said apron structure, and in said traveling grate means, means for forcing air through said perforations to promote and continue the burning thereof over the entire structure, and stationary scrapers adjacent said grate means for transferring coals from the inner to the outer edges thereof and for removing ashes from said outer edge.
- 30 35 40 45 50
